STENCILING MACHINE

Filed March 26, 1923

2 Sheets-Sheet 2

UNITED STATES PATENT OFFICE.

JOHN WALKER INGLESBY, OF NORFOLK, VIRGINIA.

STENCILING MACHINE.

Application filed March 26, 1923. Serial No. 627,923.

To all whom it may concern:

Be it known that I, JOHN WALKER INGLESBY, a citizen of the United States of America, residing at Norfolk, in the county of Norfolk and State of Virginia, have invented certain new and useful Improvements in Stenciling Machines; and I do hereby declare that the following is a full, clear, concise, and exact description of the invention, 10 such as will enable others skilled in the art to which it appertains to make and use the same.

This invention relates to improvements in stenciling devices, and has for an object to 15 provide a portable machine for stenciling matter upon bales, boxes, cartons, et cetera, in an effectual manner and in a materially less time than is now consumed by the prevalent method of placing a stencil upon the 20 article to be stencilled and painting by hand over the same.

It is likewise an object of the invention to provide a machine of the character mentioned adapted to effect the automatic moving of the particular stencil being employed by or past the ink or paint supplying and applying means, whereby when the machine is moved over the surface to be stencilled, the desired matter will be properly placed 25 thereon.

Another and equally important object of the invention is to provide one of the stencil receiving rollers or drums with an automatic brake means whereby when the stencil has been completely transferred, further movement of the strip from the feeding 30 roller or drum will be prevented and in consequence, rupturing or damaging of the same prevented.

Other objects will be in part obvious and in part pointed out hereinafter.

In order that the invention and its mode of operation may be readily understood by persons skilled in the art, I have in the accompanying illustrative drawings, and in the detailed following description based thereon, set out one possible embodiment of the same.

In these drawings:

Figure 1 is a vertical longitudinal section through the improved machine;

Figure 2 is a vertical transverse section therethrough;

Figure 3 is a fragmentary longitudinal section through the stencil feeding strip

roller of the machine and the spring clip employed for securing the adjacent ends of the stencil thereto;

Figure 4 is a disassembled detail in perspective of one of the stencil securing clamps; 60

Figure 5 is an enlarged fragmentary detail in vertical section showing the mounting of one of the vertically slidable pins with the ring in spiral way of the adjacent roller;

Figure 6 is an enlarged fragmentary detail in transverse section through the mounting of the connecting pin; and,

Figure 7 is a fragmentary detail in elevation showing the manner in which the pin receiving collar is slidably engaged and 70 mounted.

Having more particular reference to the drawings, in connection with which like characters of reference will designate corresponding parts throughout, the improved 75 machine may be stated to comprise a housing 1, substantially rectangular in shape and having the bottom thereof open, as clearly shown in the Figure 1. A knob or hand piece 2 is arranged upon the upper side and forward end of the housing, while angle brackets 3 are arranged upon the upper side of the rearward portion of the housing and pivotally support therebetween a hand grip or handle 4.

Housing or supporting rollers or wheels 5 are mounted upon the inner ends of stub axles 6 secured to the opposite side portions of the housing 1 intermediate their ends and as will be noted, have the lower portions 90 thereof extended slightly beyond or below the lower portion of said housing, whereby to provide a movable support for the same in order that it may be freely moved over a surface to be stencilled. To the inner side 95 of one of these wheels 5, there is secured a circular gear 7, screws 8 being passed through portions of the gear into engagement with complementally screw threaded openings formed in the web portion of said wheels receiving the same; the gear being of a diameter slightly less than that of the wheel receiving it and serving for a purpose which will be hereinafter more fully described.

Rotatably mounted in the opposite ends of the housing 1 and arranged within the same are transversely disposed rollers 9 and 10, formed of rubber, composition or other suitable material and having tread members 110

11 arranged upon the opposite extremities thereof for an obvious purpose.

Each of these rollers 9 and 10 are hollow and the roller 9 has a clock spring 11' arranged within the same as shown in the Figures 1 and 3 and the outer end of said spring is secured to an adjacent portion of the roller as indicated at 12, while the inner end of the same is secured to an adjacent portion of the side supporting it, as indicated at 13. Thus, it will be understood that with rotation of the roller in one direction, the clock spring 11' will be placed under a tension such as will cause rotation 15 of the roller in an opposite direction with disengagement of its tread elements 11 from a surface over which the machine is traveling.

A stencil strip of pliable or flexible material, not shown, is adapted to be employed in connection with the machine and is adapted to be normally coiled or wound about the intermediate peripheral portion of the supplying or feeding roller 9 and to effect 25 connection of the inner end of said stencil strip with the roller, I provide said roller with a longitudinally disposed peripherally arranged clamping plate 14 having spaced dovetail shaped lugs 15 arranged upon the 30 upper side of its opposite end portions adapted to be slidably engaged in the longitudinally disposed dovetail shaped groove of a moveable clamping strip 16. Thus, when the inner end of the stencil strip is engaged 35 between the clamping plates 14 and 16 positive connection as between the inner end of the stencil strip and the roller 9 will be effected. To limit the extent of sliding engagement of the clamping plate 16 with the 40 lugs 15 of the plate 14, a stop pin 17 is preferably engaged with one end of the plate 14 and is received in a pocket or recess 16' in the corresponding end of the plate 16.

That end of the roller 9 opposite to the 45 one receiving the spring 11' in it has formed in the end wall thereof, a spiral groove or way 18, the inner end of said spiral groove being arranged at a point adjacent the engagement of the axle of the roller therethrough, while the outer end of the groove is 50 arranged at a point in proximity to the peripheral portion thereof.

An elongated slot 19 is formed in the corresponding portion of the adjacent side wall of the housing 1 and has secured adjacent thereto, a substantially rectangular guide bracket 20 slidably receiving a collar 21 therein which, as will be noted, is provided with oppositely disposed fingers 21' 55 which are adapted to be engaged in guide grooves formed upon the opposite sides of said bracket 20. An anchoring plate, corresponding in shape and design to the plate 20 and indicated by the numeral 20' is secured to the opposite or inner side of the 60 adjacent wall of the housing 1, a common fastening means, such as rivets, screws or the like serving to interconnect both plates 20 and 20' through the adjacent portion of the side wall of the housing. Loosely engaged in the opening formed in the vertical 65 slidable collar 21 is a pin 22, of a length such as will permit the inner end thereof to be engaged in an adjacent portion of the spiral way or groove 18. To prevent outward lateral movement of said pin 22 with respect to the collar 21 and hence, disengagement from the spiral way or groove 18, a curved spring plate or arm 23 is pivoted to the upper end or bracket 20, as shown in 70 the Figure 5, the lower end of such spring arm being engaged over the headed outer end of the pin 22 and in consequence, retaining the same in its innermost position with respect to the collar 21 and therefore, 75 engaged with the spiral groove or way 18.

Because of the engagement of the inner end of the pin 22 in the spiral way or groove 18, it will be understood that with rotation of the roller 9 in one direction, the 80 vertically slidably mounted pin 22 will be permitted to ride upwardly in the bracket plate 20 and follow the spiral way 18 until the outer end thereof is reached. At this point, further rotation of the roller 9 in the 85 aforesaid direction will be prevented and in consequence, an effectual form or check will be provided for by the rotary movement of said roller. Hence, excessive unwinding of the stencil strip from the roller 9 with the 90 resultant probable tearing or rupturing of the same will be avoided. When the roller 9 is rotated in an opposite direction, the pin 22 now in its uppermost position in the 95 plate 20 will be permitted to move downwardly in the bracket plate 20 until the same engages the inner end of the spiral groove or way 18, thus checking or limiting the rotative movement of the roller in 100 this latter direction and in consequence, preventing the possible or probable tearing or rupturing of that portion of the stencil strip secured to the receiving or stencil strip removing roller 10, hereinafter more fully 105 described. In order that the rotative movement of the roller 9 may be varied, I may and preferably do form openings or pockets 110 24 in the bottom of several portions of the spiral way 18 and when desired, insert stop pins or plugs 24' therein, against which the 115 inner end of the pin 22 will abut and thus, limit or regulate the rotative movement of the roller 9.

A receiving or stencil strip moving roller is constituted by the roller 10, which, as will 120 be noted, is provided with an end wall having a spiral way or groove 18' formed therein corresponding to the spiral way 18 and in which the inner end of a connecting pin corresponding to the pin 22 having vertical 125 130

slidable mounting in the adjacent portion of the corresponding side wall of the housing 1 is engaged. Thus, it will be understood that the rotative movement of the roller 10 will be limited by the engagement of the connecting pin with the opposite end of the spiral way or groove 18'. Furthermore, pockets 24^a are formed in the bottom of certain portions of the groove 18' and are 10 adapted to receive in either thereof a stop pin 24^b corresponding to the pin 24' described in connection with the roller 9.

A stencil strip connecting device in form of slidably inter-engageable clamping plates 14 and 16 is arranged longitudinally of the peripheral portion of the roller 10, such arrangement corresponding to the clamping means noted in connection with the plates 14 and 16 of the roller 9. These clamping plates 14 and 16, arranged upon the roller 10, as will be understood serve as means for effecting connection between the free end of the stencil strip and said receiving roller 10 whereby the strip may be caused to unwind from the roller 9 and to wind about the intermediate portion of the receiving roller 10, such movement of the stencil strip from the supplying or feeding roller 9 to the receiving roller 10 causing the former roller to be rotated in a direction such as will place the clock spring 11' within the same under tension whereby when said feeding roller is disengaged from the surface over which the machine is travelling, it will immediately 35 function to cause reverse rotation of the feeding roller with the resultant rewinding of the stencil strip about the same to render the machine ready for a further stenciling operation.

40 A hollow vertically disposed and slidable shaft 26 is mounted in the intermediate portion of the upper side of the housing 1 and as will be noted, has a portion thereof formed substantially squared in cross section; the upper end of the shaft being normally extended about the upper side of the housing top as shown in the Figure 2 and having a collar 26' movably engaged therewith, while upon the lower extremity of the vertically slidable hollow shaft 26, there is formed a shouldered screw threaded extension 27 which is adapted to be engaged in the cover plate or closure of the hollow head or reservoir 28 of the fountain feed or supply brush, the bristles of which are indicated at 29, and as shown, are suitably engaged through a screw threaded fastening ring to the under side of said hollow head or reservoir 28.

60 Splined to the squared portion of the vertically moveable hollow shaft 26 and arranged within the housing 1 is a bevelled gear 30 meshing with a corresponding gear 31 mounted upon the adjacent end of a transversely disposed horizontally positioned

shaft 32 mounted in bearing brackets 33 secured to the under side of the housing top as shown in the Figure 2 and having the outer ends thereof engaged in suitable bearings in the corresponding side wall of said housing; a pinion 34 being fixedly mounted upon the outer end of said shaft 32 and meshing with the circular gear 7 secured to the inner side of the adjacent wheel 5.

As stated, the hollow shaft 26 is adapted to have vertical sliding movement with respect to the housing supporting the same and in order that it will be guided in such movement, there is secured to the adjacent portion of the under side of the housing top 70 1, a substantially U-shaped bracket 26^a having an opening formed in its basal portion for receiving the lower portion of said hollow shaft 26 therethrough, while its free extremities are provided with angularly disposed feet 26^b receiving suitable fastening devices therethrough, which in turn, are also engaged with adjacent portions of said housing top. A coiled spring 27' is interposed between the outer and lower portion of the handle 4 and the top of the housing 1 and serves to impart an upward thrust to the handle and the shaft 26 and in consequence, hold the latter together with the fountain supply brush in their uppermost positions 85 90 within the housing 1.

Extended through the hollow shaft 26 is a needle valve 35, the lower end of which is adapted to be normally engaged in a discharge way or port 36 formed in the lower side of the reservoir 28 of the fountain supply brush whereby to prevent the discharge of ink, or paint, or other marking material therefrom. The upper end portion of this needle valve 35 is screw threaded, as indicated at 37, and is adapted to be turned into engagement with an adjusting nut 38 arranged upon the upper side of a substantially U-shaped bracket 39 secured to the upper side and intermediate portion of the housing top as indicated at 40, a head or finger piece 41 being carried upon the upper end of said needle valve whereby to facilitate engagement and rotation of the same. Thus, it will be understood that by reason of the screw threaded engagement of the needle valve 35 with the adjusting nut 38, its relative positioning with respect to the discharge port 36 in the reservoir 28 may be varied, such as conditions or preference may dictate, as for example, to decrease or increase the flow of marking fluid from the reservoir onto the brush bristles 29.

110 A short tube 29' is embedded in the rubber or other composition employed in securing the brush bristles 29 in the externally screw threaded securing ring, heretofore mentioned, and as will be noted, is adapted to have the upper end thereof arranged at 115 a point directly adjacent and below the port 120 125 130

36 formed in the bottom of the head of the fountain feed brush, whereby, with the opening of said port, the conduction of ink or other marking fluid to the bristles and 5 through the hardened securing composition will be ensured. In this connection, it is to be noted that the bottom of the head of the fountain feed brush has an internally screw threaded circular flange 28' formed adjacent 10 the upper side thereof, which internally screw threaded flange is adapted to be turned into engagement with the correspondingly screw threaded lower portion of the reservoir of the fountain feed brush 15 28, as shown in the Figure 2.

Furthermore, diametrically disposed fingers 28^a may be and preferably are secured to the outer side of the bottom of the reservoir of the fountain feed brush head and 20 obviously serve as means for facilitating the connection of a spanner wrench or similar tool thereto whereby said bottom of the reservoir may be turned into engagement with the screw threaded portion or out of engagement therewith, as may be required.

Secured to the opposite sides of the pivotally mounted hand grip 4 are arms 42 carrying plate 43 upon their inner ends said plate having bearing upon the rounded upper end of the slidable hollow shaft 26; an opening being formed in the plate 43 whereby to permit the passage of the needle valve 35 therethrough into engagement with the adjusting nut 38, hereinbefore identified.

35 Felt or other absorbent rollers 44 are disposed transversely of and within the opposite ends of the housing 1, being mounted upon hollow shafts 45 likewise extending transversely of said housing and having 40 their opposite ends journaled in suitable bearings formed in the adjacent portions of the opposite side walls of such housing; it being noted in this connection, that the positioning of the rollers 44 and their respective shafts 45 is such as to bring the former directly adjacent the peripheral portions of the rollers 9 and 10 and thus serve to remove any surplus of ink remaining upon the stencil strip employed subsequently to or 45 immediately following a stenciling operation.

The operation of my improved stenciling machine may be reviewed as follows:

A stenciling strip is coiled about the feeding or supplying roller 9, the inner end thereof having been secured to said roller through the medium of its clamping plates 14 and 16. The free end of such stencil strip is now pulled from the roller 9 longitudinally of 55 the housing 1 and over or past the bristles 29 of the fountain feed brush, whereas said free end of the stencil strip is engaged with the receiving roller 10 through the medium of its particular clamping plates 14 and 16. 60 65 With the stencil strip so connected, it is to be

noted that the vertically sliable pins 22 engaging in the spiral ways or grooves 18 and 18' of the rollers 9 and 10 respectively will be at points adjacent the inner ends of such grooves. The machine is now ready for use. 70 At this time, the hand grip 4 is engaged in one hand of a user of the device and upon pressing downwardly thereon, the same will be rocked in a forwardly direction, causing the outer ends of the arms 42 and the plates 43 to impart a downward thrust to the yieldably mounted and vertically slidable hollow shaft 26. Such movement of the hollow shaft 26 will cause the fountain supply rotatable brush to be moved downwardly to a 75 point whereat the bristles 29 will contact with the adjacent side of that portion of the stencil strip spanning the space between the feeding roller 9 and the receiving roller 10, causing the port 36 to be disengaged from the needle valve 35 and in consequence, permitting the flow of marking fluid from the reservoir 28 onto the brush bristles. At this time, the machine is pushed over the surface to be stencilled causing the wheels 5 thereof to 80 be rotated and in consequence, effecting the transmission of rotary motion by way of the gearing 8 and 34 to the bevelled gearing 31 and 30 and thence, to the vertically disposed hollow shaft 26, whereby to effect rotation 85 of the horizontally positioned fountain supply brush in order that the bristles 29 thereof will be moved over the stencil strip and upon being saturated with the marking fluid, will serve to effectually paint the marking 90 fluid through the openings in the stencil strip upon the surface to be marked. As the machine is moved over a surface to be stencilled, it will be understood that the stenciling strip will be advanced past the now rotating fountain supply brush, passing from the feeding roller 9 onto the receiving roller 10 and causing the clock spring 11' within the feeding roller to be placed under an increasing tension. 95 With continued movement of the machine over a surface, the movement of the stencil strip by the brush bristles will continue until the stenciling operation is completed, whereupon the several rollers 9 and 10 will have rotated sufficiently to cause inward travel of their respective pins 22 in the spiral grooves 18 and 18' to points engaging the inner ends of each, whereupon such engagement of the pins 22 with the inner ends of said spiral grooves 18 and 18' will immediately serve to prevent any further rotation of the feeding roller 9 and the receiving roller 10, hence, preventing any further removal of the stencil strip from the feeding roller 9 and in consequence, avoiding disengagement of the previously mentioned inner end of said stencil strip from the roller 9 or the rupturing or damaging of such strip at either of its points of connection. 100 However, when the machine is 105 110 115 120 125 130

- removed from the stencilled surface, the feeding roller 9 will be immediately rotated in a reverse or counter direction through the medium of the tensioned clock spring 11' connected thereto and in consequence, it will be understood that that portion of the stencil strip coiled or wound about the receiving roller 10 will be returned to its original position about the feeding roller 9 and likewise, that the pin 22 of the rollers 9 and 10 will be caused to travel through the spiral ways or grooves 18 and 18' until they engage the inner end of the same and hence, prevent any further rotative movement thereof, together with the eliminating of any possibility of damaging the stencil strip. Thus, the stenciling machine is ready for a further operation, since with disengagement of the user's hand from the hand grip 4, the same will be immediately swung to its normal position and likewise, the expansible coiled spring 27' will return the handle 4 and the vertically moveable hollow shaft 26 together with the fountain supply brush to their respective uppermost positions, thereby causing reseating of the needle valve 35 in the discharge port 36 of the brush reservoir 28 and discontinuing the discharge of marking fluid onto the brush bristles 29.
- Manifestly, the construction shown is capable of considerable modification and such modification as is within the scope of my claims, I consider within the spirit of my invention.
- 35 I claim:—**
1. A stenciling machine comprising a housing, rollers mounted in the opposite ends of said housing movably supporting the same, a horizontally movable brush positioned and supported within said housing between said rollers, a reservoir upon the brush communicable with the bristles thereof, and automatically operable valve means within said reservoir for controlling the flow of marking fluid therefrom onto said bristles.
  2. A stenciling machine comprising a housing, rollers rotatably mounted in the opposite ends of said housing movably supporting the same, a horizontally movable brush supported within the housing between said rollers, said brush being also mounted for vertical movement with respect to said housing, a reservoir upon the brush communicable with the bristles thereof, and valve means within said reservoir for controlling and regulating the flow of marking fluid therefrom onto said bristles.
  3. A stenciling machine comprising a housing, rollers mounted in the opposite ends of said housing movably supporting the same, a marking fluid applying brush movably supported within the housing between said rollers, a reservoir upon the brush communicable with the bristles thereof, and valve means within said reservoir for controlling and regulating the flow of marking fluid therefrom onto said bristles.
  4. A stenciling machine comprising a housing, rollers mounted in the opposite ends of said housing movably supporting the same, a marking fluid applying brush movably supported within the housing between said rollers, a reservoir upon the brush communicable with the bristles thereof, and valve means within said reservoir for controlling and regulating the flow of marking fluid therefrom onto said bristles.
  5. A stenciling machine comprising a housing, rollers mounted in the opposite ends of said housing movably supporting the same, a horizontally movable brush supported within the housing between said rollers, said brush being also capable of vertical movement with respect to said housing, a reservoir upon the brush communicable with the bristles thereof, valve means within said reservoir for controlling and regulating the flow of marking fluid therefrom onto said bristles, and means connected to said valve means operated from a point exteriorly of said housing for automatically actuating the same.
  6. A stenciling machine comprising a housing, transverse rollers rotatably mounted in the opposite ends of said housing having their lower portions extended beyond the lower portion of such housing, spring means connected to one of said rollers for rotating the same in one direction, a vertically adjustable horizontal rotatable fountain supply brush mounted in said housing intermediately of the rollers, means for regulating the supply of marking fluid to the brush bristles, and other means for transmitting rotary motion to said brush with movement of the housing over a surface.
  7. A stenciling machine comprising a housing, transverse rollers rotatably mounted in the opposite ends of said housing having their lower portions extended beyond the lower portion of such housing, spring means connected to one of said rollers adapted to be placed under a tension sufficient at times to cause rotation of the roller in one direction, a vertically adjustable horizontal rotatable fountain supply brush mounted in said housing intermediately of the rollers, the remaining of said rollers having brake means arranged thereon for interrupting rotary motion thereof at a predetermined period, means for regulating the supply of marking fluid to the brush bristles, and other means for transmitting rotary motion to said brush with movement of the housing over a surface.
  8. A stenciling machine comprising a housing, transverse rollers rotatably mounted in the opposite ends of said housing hav-

ing their lower portions extended beyond the lower portion of such housing, spring means connected to one of said rollers adapted to rotate the same in a reverse direction, 5 at times, a spiral groove formed in one end wall of one of said rollers, a connecting pin mounted for vertical sliding movement in the corresponding portion of the adjacent side wall of said housing having its inner 10 end engaged in said spiral groove, a vertically adjustable horizontal rotatable fountain supply brush mounted in said housing intermediately of the roller, means for regulating the supply of marking fluid to the 15 brush bristles, and other means for regulating rotary motion of said brush with movement of the housing over a surface.

9. A stenciling machine comprising a housing, transverse rollers rotatably mounted in the opposite ends of said housing having their lower portions extended beyond the lower portions of such housing, spring means connected to one of said rollers for rotating the same in a reverse direction, at 20 times, one of said rollers having a spiral groove formed in one end wall thereof, a pin mounted for vertical sliding movement in the corresponding portion of the adjacent side wall of said housing having its inner 25 end engaged in said spiral groove, supporting wheels mounted adjacent the inner faces of the opposite sides of said housing intermediate its ends, a vertically adjustable horizontal rotatable fountain supply brush 30 mounted in said housing intermediately of the rollers, means for regulating the supply of marking fluid to the brush bristles, and motion transmitting means connecting said rotatable brush with one of said wheels 35 40 whereby to effect rotation of the former with movement of the housing over a surface.

10. A stenciling machine comprising a housing, transverse feeding and receiving rollers mounted in the opposite ends of said housing having their lower portions extended beyond the lower portion of such housing, a vertically adjustable horizontal rotatable fountain supply brush mounted in said housing intermediately of the feeding 45 and receiving rollers, means for transmitting a downward thrust to said rotatable horizontal brush, at times, other means for regulating the supply of marking fluid to the brush bristles, and still other means for 50 transmitting rotary motion to said brush with movement of the housing over a surface.

11. A stenciling machine comprising a housing, transverse feeding and receiving 55 rollers rotatably mounted in the opposite ends of said housing having their lower portions extended beyond the lower portion of such housing, a vertically disposed shaft slidably mounted in the intermediate portion 60 of the top of said housing, a horizon-

tally positioned fountain supply brush, the lower end of said shaft engaging the upper side of the reservoir head of the fountain supply brush, spring means connected to the shaft for normally retaining the same in its 70 uppermost position, a hand grip pivotally mounted on the upper side of the housing also connected to said spring means, arms extending from said hand grip and connected to the upper end of said vertically moveable shaft, means for regulating the supply of marking fluid to the brush bristles, and other means for transmitting rotary motion to said brush with movement of the housing over a surface. 80

12. A stenciling machine comprising a housing, transverse rollers rotatably mounted in the opposite ends of said housing having their lower portions extended beyond the lower portion of such housing, a slideable vertically disposed shaft mounted in the intermediate portion of the top of said housing, such shaft being hollow, a horizontal fountain supply brush, the upper side of the reservoir head of such brush being 85 connected to the lower end of said vertical shaft, the lower side of the reservoir head of the fountain supply brush having a discharge port therein, a needle valve extending through said hollow vertical shaft and 90 normally engaged in said discharge port, a bracket carried upon the upper side of the housing top for adjustably supporting said needle valve, a hand grip pivotally mounted upon the upper side of said housing top, spring means interposed between one portion of said hand grip and the top of said housing for normally imparting an upward thrust thereto and retaining the same together with said horizontal brush in 95 their uppermost positions, arms extending from said hand grip and engaged with the free upper end of said vertical shaft, adapted, at times, to impart a downward thrust to the same, and means for transmitting 100 rotary motion to said brush with movement of the housing over a surface. 105

13. A stenciling machine comprising a housing, transverse rollers rotatably mounted in the opposite ends of said housing having their lower portions extended beyond the lower portion of such housing, spring means connected to one of said rollers for rotating the same in a reverse direction, at 110 times, certain of the end walls of each of said rollers having oppositely disposed spiral grooves formed therein, vertically slideable connecting pins mounted directly adjacent said ends of the rollers having the spiral grooves therein in the corresponding side wall of said housing, the inner ends of each of said pins engaging in their respective spiral grooves, supporting wheels mounted adjacent the inner faces of the opposite sides of said housing intermediate its ends, a ver- 115 120 125 130

- tically adjustable horizontally rotatable fountain supply brush mounted in said housing intermediate of the rollers, means for regulating the supply of marking fluid to the brush bristles, and motion transmitting means connecting said rotatable brush with one of said wheels whereby to effect rotation of the former with movement of the housing over a surface.
- 10 14. A stenciling machine comprising a housing, transverse rollers rotatably mounted in the opposite ends of said housing having their lower portions extended beyond the lower portion of such housing, spring means connected to one of said rollers adapted to rotate the same in a reverse direction, at times, certain of the end walls of each of said rollers having oppositely disposed spiral grooves formed therein, slotted vertically disposed bracket plates secured to the corresponding side wall of said housing adjacent openings formed therein and arranged in proximity to said spiral grooves in the ends of said rollers, collars mounted for vertical sliding movement in said bracket plates, connecting pins carried by said collars having their inner ends engaged in the adjacent portions of the spiral grooves, means for removably securing said pins in engagement with their respective collars, a vertically adjustable horizontal fountain supply brush mounted in said housing intermediately of the rollers, means for regulating the supply of marking fluid to the brush bristles, and other means for transmitting rotary motion to said brush with movement of the housing over a surface.
- 15 15. A stenciling machine comprising a housing, transverse feeding and receiving rollers rotatably mounted in the opposite ends of said housing having their lower portions extended beyond the lower portion of such housing, spring means connected to one of said rollers adapted to be placed under a tension sufficient to cause rotation of said
- 20 roller in a reverse direction, at times, the ends of each of said rollers having spiral grooves formed therein, portions of said spiral grooves having pockets formed in the bottoms thereof, plugs adapted to be engaged in said pockets, at times, removable connecting pins mounted for vertical sliding movement in the corresponding portions of the adjacent side walls of said housing having their inner ends engaged in said spiral grooves, stencil strip connecting means arranged upon said feeding and receiving rollers, a vertically disposed shaft slidably mounted in the top of said housing, a horizontally positioned fountain supply brush, the upper side of the reservoir head of said supply brush being connected to the lower end of said shaft, said vertical shaft being hollow, a needle valve extending through the vertical shaft into the reservoir of said fountain supply brush and engaging the discharge port thereof, the upper portion of said needle valve being screw threaded, a bracket secured to the upper side of said housing and having a screw threaded adjusting nut thereon receiving said screw threaded upper portion of the needle valve therein, a hand grip pivotally mounted upon the upper side of said housing, a spring interposed between the free lower portion of said hand grip and a portion of the top of said housing, for normally retaining said hand grip in its uppermost position, arms extending from said hand grip and engaged with the upper end of said vertically slidably shaft adapted to impart a downward thrust thereto, at times, and means for transmitting rotary motion to said horizontal fountain supply brush with movement of the housing over a surface.
- 25 30 35 40 45
- 50 55 60 65 70 75 80 85

In witness whereof, I have hereunto set my hand.

JOHN WALKER INGLESBY.
